UNITED STATES PATENT OFFICE.

JOSHUA K. CLUTTS, OF DETROIT, MICHIGAN.

CUPOLA-CHARGING CAR.

Application filed September 21, 1925. Serial No. 57,586.

This invention relates to devices for charging cupolas, and particularly relates to cupola charging cars.

It is an object of the invention to provide a receptacle for a heavy cupola charge, to provide for introducing the loaded receptacle into a cupola through the charging door-way of the latter, and to provide a control means remote from said receptacle for releasing the contents thereof within the cupola.

Another object is to provide means under a control remote from the said receptacle for controlling the direction of its discharge within the cupola, so as to effect a proper distribution of the charge within the latter.

Still another object is to mount said receptacle and its various controls upon a suitable weighing frame, and to mount the latter upon a suitable carrying frame, preferably wheeled.

A further object is to provide such a control mechanism for the discharge from the said receptacle as will permit a ready regulation of the rate of discharge therefrom.

These and various other objects the invention attains by the construction hereinafter described and illustrated in the accompanying drawings, wherein:

Fig. 1 is a plan view of a charging car embodying the inventive features.

Fig. 2 is a view of the same in side elevation, a fragmentary portion of a cupola being sectionally shown, and the charge receptacle carried by the car being shown introduced into said cupola.

Figure 3 is a longitudinal vertical sectional view of the invention, the plane of section being indicated at 3--3 in Fig. 1.

Fig. 4 is a cross sectional view of the charging receptacle and its mounting, taken upon the line 4--4 of Fig. 3.

In these views, the reference character 1 designates a substantially rectangular hollow frame suitably mounted upon front and rear pairs of wheels 2. Within its central opening, said frame carries a weighing scale, which may be of ordinary construction. As shown, this scale comprises a pair of levers 3, extended lengthwise of the frame 1 and pivoted upon the latter at remote points 4, said levers being pivotally connected as indicated at 5. Suitably located pivot bearings upon said levers carry a weighing frame comprising a pair of elongated spaced sills 6 and suitable cross members 7 connecting said sills.

The forward portions of the sills 6 project some distance beyond the frame 1 and form a mounting for a rotatable cylindrical receptacle 8 for the cupola charge. This mounting is established preferably by exteriorly providing upon said receptacle two vertically spaced supporting rings 9, which, as shown, are of angle bar cross section and which rest upon sets of rollers 10 radially journaled in upper and lower channel-shaped rings 11, the former seating directly upon the sills 6 and the latter being carried by a sub-frame 12 depending from said sills.

The bottom of the receptacle 8 is formed by a pair of downwardly opening doors 13, copivottally mounted upon a rod 13^a diametrically carried by the lower end of the receptacle. Preferably the bottom edge of the receptacle inclines slightly upwardly at each side of said rod, so that the closures 13, when seating against said edge, are correspondingly inclined.

The mechanism for controlling the closures 13 comprises two duplicate pairs of links 14, the remote ends of said links being pivoted to said closures equidistantly from the rod 13^a and the links of each pair converging downwardly from the doors to pivotally engage a rod 15, adapted to actuate said links 14 to close or open the closures 13, according as said rod is raised or lowered. Midway of its length, said rod is engaged by a chain 16 which extends vertically upward through the receptacle 8 in proximity to a partition 17 diametrically secured within the receptacle and extending at its lower edge in close proximity to said rod. Above said receptacle, the chain 16 is carried over a guide pulley 18 attached to a frame 19 mounted upon the scale sills 6 and forming an arch above said receptacle. From said pulley, the chain extends rearwardly to a drum 20 upon which its rear end portion is wound and by rotation of which the closures 13 may be raised or lowered. Said drum is journaled in a pair of suitable uprights 21 mounted upon the scale frame, and a semi-circular brake band 22 provided with a suitable control lever 23 is engageable with said drum under regulable pressure to hold the doors 13 either fully closed or partially opened, and to permit any desired retardation of the opening movement of the doors. A provision for effecting such rotation of the drum 20 as will close the doors will presently be described.

For actuating the receptacle 8 rotatively, a chain 24 makes a number of turns about the upper portion of said receptacle and is extended rearwardly from opposite sides of 5 the receptacle, the end portions of said chain being reversely wound upon a drum 25 journaled in a pair of uprights 26 spaced upon the rear portion of the scale frame. Accordingly as said drum is driven in one direction or the other, the receptacle 8 is rotated in a clockwise or counter-clockwise direction.

For driving the described car and also (if desired) for actuating the drums 20 and 15 25, there is carried by the rear portion of the frame 1, within the central opening thereof, an electric motor 27 which may be geared as indicated at 28 to the rear axle of the car, and which may have driving connections 29 20 and 30 to the drums 20 and 25 respectively.

31 designates a step mounted upon the rear end of the frame 1 for use of the operator and 32 is a weight attached to the rear end of the scale frame to counterbalance the receptacle 8 and its contents. A gauge 33 upon which the scale indications may be read 25 30 35 mounts a post 34 rising from the frame 1, and an actuating connection from one of the scale levers 3 to the needle of said gauge is indicated at 35. The opening movement of the closures 13 is limited by suitable yieldable stop members secured to the under faces of said closures near their outer edges, said stop members abutting when the doors are 25 30 35 40 fully open and maintaining a sufficient angularity in the relation of the links 14 to insure their proper response to an upward pull exerted upon the chain 16.

In the operation of the described invention, a charge of materials to be delivered to the cupola is first introduced by any suitable means into the receptacle 8. Ordinarily 40 45 50 55 60 65 said materials will be mainly metallic, but the delivery of fuel to the cupola can also be efficiently accomplished through use of said receptacle. When the receptacle has been sufficiently loaded, the weight of its contents may be immediately obtained by consulting the gauge 33. The charging car is now driven from the point of loading to the cupola 37 (see Fig. 2) and after the charging opening 38 of the cupola has been uncovered, the charging car is driven forward, in registration with said opening so as to carry the receptacle 8 through said opening and into the cupola. The operator now establishes a drive connection to the drum 25 (if desired) whereby said drum acts through the chain 24 to rotatively shift the receptacle 8 so far as may be necessary to establish the desired direction for delivery of the charge from 60 65 said receptacle. It is to be understood that, unless the closures 13 are allowed to drop quite abruptly, said closures will exert a tendency to deflect the discharging materials

toward the cupola wall in a direction substantially transverse to the pivotal axis of said closures, so that the operator by selecting a desired diametrical relation of said axis to the cupola wall can predetermine the 70 subsequent direction of discharge. Thus for example, if at the moment of discharge, the pivot rod 13^a of the receptacle is disposed lengthwise of the car, the direction of the discharge when the doors 13 are opened gradually will be primarily toward the sides of the cupola, whereas, if the pivotal axis of the closures is transverse to the cupola sides at the moment of discharge, the materials will be deposited primarily adjacent to the front 80 and rear walls of the cupola. If it is desired to distribute the charge in a substantially uniform manner within the cupola, the doors may be allowed to fall abruptly to their open positions, so that the charge may drop 85 substantially vertically, without being subjected to deflection by the doors. The opening travel of the closures is accomplished by the weight of the load resting upon said closures, and such travel occurs as soon as 90 the operator relieves pressure of the brake 22 upon the drum 20. According as this pressure is relieved, to a greater or less degree, the opening travel of the closures 13 will be fast or slow. As soon as the receptacle 95 has been emptied, the operator applies power to the drum 20 so as to wind the chain 16 upon said drum and thus move the closures 13 to their closed positions. Finally 100 the charging car is driven back sufficiently 105 to withdraw the receptacle 8 from the cupola and the charging opening 38 of the latter is again uncovered.

As compared to the present practice of manually throwing or shoveling the charge 110 into a cupola, use of the described car accomplishes a great advance in efficiency. For every cupola, such a car eliminates necessity for several workmen (known as chargers), and permits the one man in 115 charge of said car to accomplish the charging operation in a much shorter length of time, with much less discomfort due to heat, and without the severe physical exertion required by manual charging. Furthermore use of 120 said car permits distribution of the charge within the cupola to be much more accurately controlled than is possible under conditions of manual charging, since radiation of heat through the charging opening will not permit workmen to approach said opening closely enough to permit of their throwing the charging material manually to any desired interior point. Heat radiation through 125 the charging opening will not subject the operator of the described car to appreciable discomfort, first since such radiation is largely blocked by the presence of the charging receptacle in the cupola, second, because the operator is stationed upon the rear end 130

of the car and is therefore some distance from the charging opening, and third, because the period of charging is comparatively short.

5. Owing to the mounting of the charging receptacle upon a weighing scale carried by the described car, the accurate total weight of the charge is immediately obtainable as soon as said charge has been loaded into the 10 receptacle. The advantage of this over the practice now commonly followed of transporting the charge to the cupola in wheel barrows and separately weighing each wheel barrow load will be readily evident.
15. By providing a partition in the charging receptacle directly above the door axis, the charge is prevented from clogging the doors in their pivotal movement.

What I claim is:

20. 1. In combination, a receptacle having an outlet at its lower end, a pair of downwardly opening pivotal closures controlling said outlet, and a pair of toggle links connecting said closures and establishing a common control thereof, and positioned beneath said receptacle.
25. 2. In combination, a receptacle having an outlet at its lower end, a pair of downwardly opening, substantially copivotal doors controlling said closures, a connection between said closures beneath the same for actuating the two closures in common, and control means for said connection upwardly extended through the receptacle.
30. 3. In combination, a receptacle having an outlet at its lower end, a pair of downwardly opening, substantially copivotal closures for said outlet, a pair of links beneath said closures pivoted terminally to each other and having their other ends pivoted respectively to said closures, and means connected to said links for effecting a common control of said closures.
35. 4. In combination, a receptacle having an outlet at its lower end, a pair of downwardly opening, substantially copivotal closures for said outlet, a pair of links beneath said closures having remote ends pivoted to the closures and having their other ends pivotally connected, and converging downwardly from the closures to their pivotal connected ends, and an actuating element for said links upwardly extended through said receptacle.
40. 5. In combination, a receptacle having an outlet at its lower end, a pair of downwardly opening substantially copivotal closures for said outlet, a pair of links beneath said closures having remote ends pivoted to the closures and having their other ends pivotally connected, means for actuating said links to control the closures, and means limiting the approach of the closures to each other in their opened positions, whereby a minimum angularity of the links is predetermined.
45. 6. In combination, a receptacle having an outlet at its lower end, a downwardly opening pivotal closure for said outlet, means for controlling said closure from a point remote from the receptacle, including a provision for regulating the velocity of the opening movement of the closure.
50. 7. In combination, a receptacle having an outlet at its lower end, a closure for said outlet, a flexible control element for said closure upwardly extended through said receptacle, a drum remote from the receptacle upon which a portion of said control element is wound, and a brake acting upon said drum.
55. 8. In combination, a frame, a receptacle mounted upon one end of said frame and having an outlet at its lower end, a closure for said outlet, a control element for said closure extended to the other end of said frame, and means upon the last mentioned end of said frame coacting with said control element to regulate the velocity of opening of said closure.
60. 9. In combination, a wheeled carrying frame, a weighing frame mounted upon the carrying frame and projecting at one end beyond the carrying frame, a receptacle terminally retained upon the projecting portion of the weighing frame for carrying and discharging material, means co-acting with the weighing frame for weighing the contents of said receptacle, and means independent of said weighing means carried by the other end portion of the weighing frame for counter-balancing said receptacle and its contents.
65. 10. In combination, a carrying frame, a weighing frame mounted upon the carrying frame and projecting at one end beyond the carrying frame, a receptacle carried by said projecting portion of the weighing frame having an outlet at its lower end, and means carried by said weighing frame for independently controlling the velocity and the direction of the discharge from said outlet.
70. 11. In combination, a receptacle, a pair of downwardly opening closures forming the bottom of said receptacle, pivoted substantially coaxially and in a substantially diametrical relation to said receptacle, and a partition wall arranged within said receptacle having its lower edge extended into close proximity to the axis of said closures.
75. 12. In combination, a pair of co-pivotal, normally substantially horizontal members for supporting material, a connection between said members beneath the same for actuating said members upwardly or downwardly in common, and a control means for said members, upwardly extended between said members.
80. 13. In combination, a pair of normally substantially horizontal co-pivotal members for supporting and discharging material, a pair of links beneath said members having remote ends pivoted to said members, and

having their other ends pivotally connected, means for actuating said links to control said members, and means limiting the approach of said members to each other in their lowered positions whereby a minimum angularity of the links is predetermined.

14. In combination, a carrying frame, a weighing frame mounted upon the carrying frame, and projecting at one end beyond the carrying frame, a normally horizontal pivotal support for materials carried by the projecting end portion of the weighing frame downwardly movable to discharge said materials, and means carried by one of said frames for independently controlling the velocity and the direction of the discharge of materials.

15. In combination, a pair of normally horizontal copivotal members for supporting and discharging material, a common means for pivotally raising and lowering said members, and means carried by said member for yieldably limiting their approach to each other when lowered.

16. In combination, a pair of co-pivotal members normally positioned substantially horizontally for supporting materials and pivotally movable downwardly for discharging said materials, a pair of links beneath said members pivoted terminally to each other and having their other ends pivoted respectively to said members, and means connecting the said links for effecting a common control of said members.

17. In combination, a pair of substantially co-pivotal members normally positioned substantially horizontally for supporting material, and pivotally movable downwardly for discharging such material, a pair of links beneath said members having their remote ends pivoted to said members, and having their other ends pivotally connected and converging downwardly from the closures to their connected ends, and an actuating element for said links upwardly extended between said members.

18. In combination, a vehicular carrying frame, a weighing frame mounted upon the carrying frame, and projecting at one end beyond the carrying frame in its direction of vehicular travel, a support for materials upon said projecting end portion of the weighing frame, means upon the body portion of one of said frames controlling the discharge of materials from said support, and means carried by the weighing frame at its end remote from the material support, for counterbalancing said support and its contents.

19. In combination, a frame, means for portably supporting said frame, said frame having an end portion forming a substantially rigid part of said frame projecting beyond said supporting means, a normally substantially horizontal member pivoted

upon the projecting end portion of said frame for carrying material, and means upon the main body portion of said frame for pivotally lowering said member to discharge its load therefrom, and guide means for the last-named means upon said projecting end portion.

20. In combination, a frame, means for portably supporting said frame, said frame having an end portion projecting beyond said supporting means, a pair of normally substantially horizontal members mounted upon the projecting end portion of said frame, and jointly forming a support for material, movable to discharge said material, and means carried upon the body portion of said frame for actuating said members in common to discharge their load.

21. In combination, a frame, means for portably supporting said frame, said frame having an end portion projecting beyond said supporting means, a member mounted upon the projecting end portion of said frame, rotatable about a substantially vertical axis, a normally substantially horizontal support for material, pivoted upon said rotatable member, and downwardly pivotally movable to discharge its load, means carried by the body portion of said frame for rotatably actuating said rotatable member, and means carried by the body portion of said frame for controlling the discharge of material from said support.

22. In combination, a frame, means for portably supporting said frame, said frame having an end portion projecting beyond said supporting means, a receptacle rotatably mounted upon the projecting end portion of said frame, and having a provision for the discharge of its contents, means carried by the main body portion of said frame controlling the discharge of materials from said receptacle and a cable having a portion embracing said receptacle and having end portions extending to the main body of said frame, and alternatively actuatable to rotate the receptacle in either direction.

23. In combination, a vehicular carrying frame, means carried by said frame for effecting its vehicular travel, a weighing frame mounted upon the carrying frame and projecting at one end beyond the carrying frame in its direction of vehicular travel, a support for materials upon said projecting portion of the weighing frame, and means upon the body portion of one of said frames controlling the discharge of material from said support.

24. In combination, a carrying frame, a weighing frame, mounted upon the carrying frame, and having an end portion projecting beyond said carrying frame, a pair of normally substantially horizontal members pivoted upon the projecting portion of the weighing frame, and forming a support for

materials, and pivotally downwardly movable to discharge and means upon the body portion of one of said frames controlling the discharge of materials from said support.

- 5 25. In combination, a carrying frame, a weighing frame, mounted upon the carrying frame, and having an end portion projecting beyond the carrying frame, a normally substantially horizontal support for materials pivotally mounted upon said projecting portion of the weighing frame for carrying materials and downwardly pivotally

movable to discharge its load, said support being mounted for rotation about a substantially vertical axis, means upon the body portion of one of said frames for controlling raising and lowering of said support, and means upon the body portion of one of said frames for rotatively actuating said support to control the direction of discharge of its load.

In testimony whereof I sign this specification.

JOSHUA K. CLUTTS.
